UNITED STATES PATENT OFFICE.

A. H. SASSAMAN, OF SCRANTON, ASSIGNOR TO HIMSELF, AND BASSLER BOYER AND JOHN STROUD, OF LEBANON, PENNSYLVANIA.

IMPROVED JOURNAL-BOX.

Specification forming part of Letters Patent No. 97,968, dated December 11, 1869.

To all whom it may concern:

Be it known that I, AMBROSE H. SASSAMAN, of Scranton, in the county of Luzerne and State of Pennsylvania, have invented a new and valuable Improvement in Anti-Friction Machinery, (Box, &c.;) and I do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal section of my device. Fig. 2 is a cross-section of the same.

My invention relates to journal-boxes and shafts for cars and machinery; and it consists, mainly, in the construction and arrangement of a series of grooves both in such shaft and box, in which I adjust a continuous series of loose rollers, so arranged that they shall rotate in said grooves without axles or pivots, the object being to lessen friction, and thereby save the labor and expense of lubrication.

My journal-box is formed in two sections, which on the drawings are marked A and B, respectively. On the inner sides of these sections I cut grooves, usually three in number, leaving flanges between them to serve as guides for the rollers, hereinafter mentioned. My shaft is also constructed with grooves of suitable depth and of a length and in number

corresponding with the grooves formed in the journal-box above described. When adjusted in place, the grooves in the shaft are directly opposite the grooves in the box.

The letters *a* are small rollers arranged in the grooves of the box and the shaft. They have no axles or pivots, and are guided in their movements by the flanges upon the box and shaft formed by cutting out the grooves above mentioned. These rollers fill the entire spaces formed by the grooves of the box and shaft, leaving only a small space between their ends and grooved flanges and a very small space between themselves. They are so arranged that they touch each other when at rest, leaving only a minute space between the two rollers immediately at the top of the shaft.

What I claim as my invention, and desire to secure by Letters Patent, is—

The combination and arrangement of the grooved journal-box and shaft herein described with the rollers *a*, all constructed and operating substantially as and for the purposes specified.

In testimony that I claim the above I have hereunto subscribed my name in the presence of two witnesses.

A. H. SASSAMAN.

Attest:

BASSLER BOYER,
ANTHONY S. ELY.
